UNITED STATES PATENT OFFICE

JESSE D. LANGDON, OF LOS ANGELES, CALIFORNIA

SHAVING KIT

Application filed July 14, 1928. Serial No. 292,788.

The present invention relates to shaving kits, and aims to provide a shaving kit having a novel arrangement and assembly of the component element for advantage and convenience in the use of the outfit.

Another object is the provision of a shaving kit including a permanent magnet within the magnetic field of which the razor blades are disposed to subject the blades and particularly the edges thereof to the magnetic flux, so as to have a tendency to maintain the edges of the blades in good condition. A further object, in this connection, is to take advantage of the magnet for a blade held in the head of a safety razor, for extra razor blades, and for a razor blade within a blade sharpener, to which ends the safety razor, extra blade holder and blade sharpener are assembled with the magnet in a manner to take advantage of the magnetic flux.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein—

Figure 1 is a plan view of the shaving kit with the cover in open position.

Fig. 2 is a cross section on the line 2—2 of Fig. 1.

Fig. 3 is a section on the line 3—3 of Fig. 1 of the blade sharpener and blade holder.

Fig. 4 is a plan view of the blade holder.

Fig. 5 is a perspective view of the blade holder showing same partly opened.

The kit includes a case or box 10 of suitable material and size, having a hinged cover or top 11, the case being of elongated form as shown with the hinge at one end. The case and cover thereof are preferably lined, as at 12 and 13, respectively, with velvet or other suitable material, and the case 10 has a spring catch 15 for holding the cover closed frictionally.

A mirror 14 is secured in any suitable man-

ner within the cover 11, preferably at that end of the cover opposite to the hinge, and the mirror may be conveniently used while shaving, with the cover 11 open, thereby supporting the mirror in an inclined position. 55 The mirror is concaved in order to give a magnified image for convenience when shaving.

In carrying out the invention a U-shaped or horseshoe magnet 16 is disposed within the case 10 with its limbs parallel to the sides of the case, and, as shown, the lining 12 is fitted snugly between the walls of the case and the permanent magnet to retain said magnet in place. The razor blades contained within the kit are disposed transversely of the limbs of the permanent magnet at the terminals or poles of said magnet, as will presently appear, in order that said blades are disposed in the field of the magnet. 70

A blade sharpener 17 is disposed across the terminals or poles of the magnet, and will be described in detail hereinafter, and a suitable filler 18 is disposed between the blade sharpener 17 and the corresponding end of the case 10 to hold the blade sharpener in place against the terminals of the magnet. 75

The safety razor, which may be of any suitable kind, is nested within the magnet, 80 the razor as shown comprising the head 19 in which the blade is clamped or held, and the usual handle 20. In order to receive and support the razor in position a holder 21 formed of sheet metal or other suitable material is fitted within the magnet 16 and has an opening 22 to receive the head 19 of the razor. The holder 21 has a groove 23 extending longitudinally from the opening 22 to receive the handle 20, and the opening 22 is located at that end of the holder 21 nearest the terminals or poles of the magnet. The razor may be readily dropped or seated in the holder 21 to be retained in position within the magnet 16 and case 10. 95

In the space between the blade sharpener 17 and razor holder 21 is disposed a holder or receptacle 24 for the extra razor blades 25, so that said blades are disposed between the terminals or poles of the mag- 100

net. The blades 25 and the blade in the head 19 are disposed transversely between the terminals or poles of the magnet, so that the lines of magnetic force pass through the blades in substantially the planes of said blades, and 5 the edges of the blades are attracted toward the limbs of the magnet, whereby the magnetic flux has a tendency to preserve the edges of the blades in good condition. The 10 magnetic flux creates a constant straightening-out pulling force on the edges of the blades, and the blades are also magnetized.

The blade sharpener 17 comprises two plates 26 of suitable sheet metal disposed together and secured together in any suitable 15 manner. As shown, opposite edges of the plates 26 are bent back around the companion edges, as at 27, for securing said plates together. The plates have the portions 28 offset away from one another and arranged 20 vertically with the sharpener 17 disposed in the case 10 as shown. The offsets 28 provide pockets in which are disposed for rotation the pairs of rollers 29 composed of carborundum or any other suitable abrasive material. 25

There are two pairs of abrasive rollers 29 for sharpening the opposite edges of a razor blade 25' inserted into the sharpener, and 30 said pairs of rollers are so spaced apart that the edges of the blades pass directly between the rollers. The plates 26 are spaced apart between the pairs of rollers 29 in order to receive the razor blade 25', thus providing a 35 guide for the blade when introduced into the sharpener. In order to accommodate the blade holder 30, the plates 26 are provided between the offsets 28 with portions 31 offset away from one another and providing a 40 guide to receive said blade holder for conveniently inserting and withdrawing the blade.

The blade holder 30 comprises the elongated members or plates 32 and 33 for holding the blade 25' between them, said members being narrower in width than the blade 45 so that the edge portions of the blade project beyond the edges of said members. The members 32 and 33 are provided at one end with the angularly extending portions 34 and 35, respectively, which are hingedly connected, as at 36, thereby permitting the members 32 and 33 to be swung together and apart, and the portions 34 and 35 provide a 50 finger piece for conveniently pushing the blade holder down into the sharpener and withdrawing the blade holder. The bend of the member 33 adjacent to the portion 35 is 55 roughened, as at 37, in order to provide a grip for the thumb to conveniently swing the member 33 away from the member 32 and blade 25', as seen in Fig. 1.

Lugs 38 are struck from the member 32 to engage through the apertures 39 in the blade 25', for properly positioning said blade within the blade holder, and the member 33 60 has apertures 40 to receive the lugs 38 when

the members 32 and 33 are swung together. The member 33 is slightly shorter than the member 32, in order that when the corresponding end of the member 32 and blade 25' are held between the thumb and first finger of one hand, as seen in Fig. 5, the opposite end of the holder may be held between the thumb and first finger of the other hand, for conveniently swinging the member 33 open, the first named thumb being beyond the end 75 of the member 33, and the second named thumb being moved under pressure in engagement with the portion 37, to swing the member 33 away from the blade. The blade 25' may then be readily removed and 80 replaced.

When a blade is disposed in the blade holder 30, the blade may be readily introduced into the sharpener 17, the holder 30 moving downwardly in the offsets 31 so as to guide the blade holder and blade in the sharpener. The edges of the blade are therefore moved longitudinally between the abrasive rollers 29 in order to sharpen the blade. The rollers 29 will also hollow-grind the edge portions of 90 the blade because the rollers present convex surfaces to the blade. The blade may be reciprocated while in the sharpener, but it may usually be sufficient to slide the blade with the blade holder into the sharpener and then 95 withdraw the blade.

The sharpener 17 being located at the terminals of the magnet 16 will also result in the magnetic flux acting on the edge portions of the blade 25' while it is in the sharpener, and 100 if it is desired to concentrate the magnetic flux on the razor blades, the razor holder 21, extra blade holder 24, plates 26 and sharpening blade holder 30 may be of brass or other 105 non-magnetic material.

The rollers 29 may also rotate in order to present the peripheral surface of the rollers to the blades throughout the peripheries of the rollers. The sharpening blade holder 30 may be deposited within the sharpener 17 110 when the device is not in use, and the abrasive rollers 29 may also be readily removed and replaced when worn out.

Having thus described the invention, what 115 is claimed as new is:—

1. A shaving kit including a horseshoe magnet, and a safety razor holder fitted within said magnet adapted to receive a safety razor with its head disposed transversely between the limbs of said magnet.

2. A shaving kit including a horseshoe magnet, and a safety razor holder within said magnet having an opening near the terminals of the magnet for receiving the head of a safety razor.

3. A shaving kit including a horseshoe magnet, and a safety razor holder within said magnet having an opening near the terminals of the magnet for receiving the head of a safety razor and having a groove extending 125

longitudinally from said opening to receive the handle of the razor.

4. A shaving kit comprising a horseshoe magnet, a safety razor within the magnet with its head near the terminals of the magnet, and extra blades between the terminals of the magnet beyond said head of the razor.

5. A shaving kit including a horseshoe magnet, a safety razor holder within the magnet for receiving a safety razor with its head near the terminals of the magnet, and an extra blade holder between said terminals of the magnet beyond the razor holder.

6. A shaving kit comprising a horseshoe magnet, and a blade sharpener disposed across the terminals of said magnet and adapted to receive a safety razor blade with its edges adjacent to said terminals of the magnet.

7. A shaving kit including a horseshoe magnet, a blade sharpener disposed across the terminals of the magnet, a safety razor located within the magnet with its head near the terminals of the magnet, and extra blades located between said head of the razor and said sharpener between said terminals of the magnet.

8. A shaving kit including a horseshoe magnet, a blade sharpener disposed across the terminals of said magnet, a safety razor holder within the magnet for receiving a safety razor with its head near the terminals of the magnet, and an extra blade holder between said sharpener and razor holder between said terminals of the magnet.

35 9. A device of the character described including a horseshoe magnet, and a razor blade sharpener, disposed across the terminals of said magnet and having abrasive means adjacent to said terminals for the contact of the edges of the blades.

In testimony whereof I hereunto affix my signature.

JESSE D. LANGDON.
